UNITED STATES PATENT OFFICE.

ALFRED MOORHOUSE, OF DETROIT, MICHIGAN, ASSIGNOR TO PACKARD MOTOR CAR COMPANY, OF DETROIT, MICHIGAN, A CORPORATION OF MICHIGAN.

INTERNAL-COMBUSTION ENGINE.

Application filed September 25, 1925. Serial No. 58,478.

This invention relates to internal combustion engines and particularly to the valve mechanism thereof.

During the past few years the top speed 5 of automobile engines has been increased from time to time, and as the speed has gone up it has been necessary to increase the spring tension on the poppet valves in order to insure the closing of the valves at the 10 higher speeds. In some cases the ability of the springs to close the valves is the thing that determines the limit of speed, and consequently some attention has been given to the matter of making lighter the reciprocating 15 valve parts.

One of the objects of the present invention is to make the reciprocating parts of the valve mechanism lighter in order that a lighter spring may be used, or that the 20 engine speed may be increased with the same spring.

Another object of the invention is to simplify the valve mechanism of an internal combustion engine.

25 Another object of the invention is to provide fewer parts in the valve adjusting mechanism to thereby simplify the construction and reduce the costs.

Other objects of the invention will appear 30 from the following description taken in connection with the drawings, which form a part of this specification, and in which:

Fig. 1 is a sectional view through a portion 35 of an internal combustion engine embodying the invention;

Fig. 2 is a transverse view on the line II-II of Fig. 1, and

Fig. 3 is a perspective view of the adjusting disk and its supporting means and 40 operating parts.

Referring to the drawings, 10 represents the crank case of an internal combustion engine and 11 is a portion of the cylinder block in which there is a valve port 12 and 45 a poppet valve 13 to close the port. A valve guide 14 is arranged in the cylinder block and the stem 15 of the valve 13 extends through the valve guide 14 as shown in the drawing. At the lower end of the valve 50 stem there is a key 16 which extends through a transverse opening in the valve stem, and this key forms an abutment for the lower end of a valve spring 17. A washer 18 is arranged between the key and the valve 55 spring end, and this washer is formed with

a recess 19 into which the key fits when in place. The upper end of the valve spring 17 abuts against the part of the cylinder block surrounding the valve stem as at 20. Thus the valve is retained in closed position. 60

In the crank case there is a cam shaft 21 rotated through suitable timing gears in the crank case (not shown) and a rocker arm 22 is supported on a pivot as at 23 in a suitable bearing in the crank case. The 65 rocker arm 22 operates against a tappet or valve operating pin 24 which is arranged in a guide 25 in the crank case 10 immediately beneath and in axial alinement with the stem 15 of the valve above described. In 70 order that the valve tappet 24 may be retained in its guide against accidental displacement when being assembled, it is formed with a groove 26 and provided with a split ring 27 in the groove. This ring is 75 arranged somewhat above the guide 25 when the tappet is in its lowest operative position so that it does not interfere with the operation of the tappet and yet it will prevent the tappet from dropping down into 80 the crank case as when the rocker arm 22 is removed for replacement or repair.

The upper end of the valve tappet 24 is arranged in close proximity with the lower end of the valve stem 15, and since it is impracticable to make these parts so that they will exactly meet, a metal disk 28 is provided between the valve stem and the valve tappet. The assembler will have several of these disks of varying thicknesses and with the 85 engine running or with the other parts in place, he will measure the space between the valve stem and the tappet and fit the desired disk into it.

The disk is retained in position by a 90 spring ring or sleeve 29 which is in turn supported from the key 16 by an extension or lug 30 on the key. As shown, the spring ring 29 is formed in two parts, each of 95 which is riveted to the lug 30. This may be 100 seen particularly in Figs. 2 and 3. The spring ring 29 does not extend all the way around the disk 28, but is open at one side so that the disk may be grasped by a pair of pliers or other tools and removed and 105 another disk replaced. At no place is the spring ring 29 in contact with either the valve stem or the tappet 24 so that there is no wear between those parts and no likelihood of the tappet catching on the spring 110

ring and displacing it. In other words, the spring ring 29 retains the disk 28 in place but is spaced from the valve stem and push rod so that it does not interfere with 5 the action of either.

All of the parts forming the adjusting means are light and there are fewer of them than in the conventional threaded adjusting means, so that the mechanism may be easily 10 and cheaply manufactured and accurately produced. Since there is no threading of the tappet 24, this part may be made much smaller in diameter and easily ground to an exact fit in its guide 25. This makes this 15 part lighter and a better fit in its bushing.

The entire mechanism is so much lighter than the conventional construction that a spring or much less tension may be used for the same engine or the same spring may be 20 used and higher speeds developed.

While I have herein described in some detail a specific embodiment of my invention, which I deem to be new and advantageous and may specifically claim, I do not desire 25 it to be understood that my invention is limited to the exact details of the construction, as it will be apparent that changes may be made therein without departing from the spirit or scope of my invention.

Having thus described my invention, what I claim and desire to secure by Letters Patent is:

1. In an internal combustion engine, the combination with the valve stem and the 35 tappet therefor, of a disk arranged between the valve stem and the tappet, and an arcuate spring carried by the valve stem, said spring partially surrounding the disk and spaced from the valve stem and tappet.
2. In an engine, the combination of a valve 40 stem, a tappet therefor, a key in one of said parts, a disk arranged between the valve stem and the tappet, and means carried by the key for retaining the disk in place.
3. In an internal combustion engine, the 45 combination of a poppet valve, a spring for closing said valve, an abutment on the valve

for one end of said spring, a key in the valve stem for supporting said abutment, a disk between the valve stem and tappet, and 50 means on said key for supporting the disk.

4. In an engine, the combination of a valve and a tappet, a disk arranged between the valve and tappet, and an arcuate spring 55 partly surrounding the disk, and means connecting the arcuate spring with the valve stem.

5. In an engine, the combination of a poppet valve, a spring for closing the valve, a key extending through the stem of the 60 valve and forming an abutment for the spring, a disk at the end of the valve stem, and a spring carried by said key partially surrounding and retaining said disk in position.

6. In an engine, the combination of a valve, a tappet therefor, a disk between the valve and tappet, a key in the valve stem, 65 said key having an extension, a spring partially surrounding said disk and retaining it in place, and means integrally connecting said spring to said extension.

7. In an internal combustion engine, the combination with the valve and the tappet therefor, of a disc arranged between the valve and the tappet, a spring for closing said valve, an abutment on the valve for one 75 end of the spring, a key in the valve stem providing a seat for said abutment, an arm on said key and an arcuate spring support 80 by said arm adapted to retain said disc in position.

8. In an internal combustion engine the combination with the valve and the tappet therefor, of a disc arranged between the valve and tappet, a spring for the valve, an abutment on the valve stem for one end of the spring, said abutment having a recess, a key in said valve fitting said recess, an arm upon said key and arcuate spring sections 85 90 upon said arm for supporting the said discs.

In testimony whereof I affix my signature.

ALFRED MOORHOUSE.
